HUG RING PLIERS

Gilbert C. Garcia, San Antonio, Tex., assignor to
The Heller Company, Cleveland, Ohio

Application August 25, 1947, Serial No. 770,354

3 Claims. (Cl. 1—187)

1

This invention relates to stapling or fastener applying devices, and more particularly to a staple applying device for use with heavy staples, as for example those known as "hug rings," adapted to the securing of material such as burlap to rods or springs, joining coil springs together or to rods, and similar applications.

An object of the invention is to provide a device of this type for use with fasteners which are partially formed and held in a magazine in side-by-side relationship, in which the mechanism for feeding the individual fasteners is very simply constructed.

For a fuller understanding of the nature and objects of the invention, reference is made to the following detailed description, taken in connection with the accompanying drawing, in which:

Fig. 1 is a plan view of the device in its normal position with a staple in the jaws, ready to be clinched;

Fig. 2 is a plan view of the device with the handles moved toward one another to effect the clinching of the staple;

Fig. 3 is a cross-sectional elevation taken on the line 3—3 of Fig. 1;

Fig. 4 is a detail view of the assembly of the spring-pressed follower;

Fig. 5 is a detail view of the jaws of the device as shown in Fig. 1, but with the upper portion cut away;

Fig. 6 is a detail view of the jaws of the device as shown in Fig. 2, but with the upper portion cut away; and

Fig. 7 is a cross sectional view on line 7—7 of Fig. 3.

Referring now in detail to the drawings, a pair of S-shaped members, constituting levers, are indicated by reference numerals 6 and 7. The member 6 is provided with a handle 8 and a jaw 9, and member 7 is provided with a handle 10 and a jaw 11. A head piece is indicated generally by the numeral 12. The base 13 of the head piece is flat and extends forwardly from the main body. A hole, provided in the forward portion of the base 13, accommodates a pivotal supporting means such as threaded pin or bolt 14 which acts as a pivot for members 6 and 7. The head of the bolt 14 is countersunk so as not to project above the surface of the base 13, and is provided with a nut 15.

Channels 16 and 17 are provided on the upper side edges of base 13, extending in parallel relationship, and may be formed integrally with the base. The channels face each other and constitute a track. The plate 18 is slidably positioned in the channels 16 and 17. Abutments 19 on the plate 18 limit forward movement. Movement of the plate 18 is coordinated with that of the members 6 and 7 by a toggle means comprising two arms 20 and 21, each of which is pivotally connected at one end to the rear end of the plate 18, by means of a rivet 22 or other suitable

fastening means. The other end of arm 20 is pivotally connected to the member 6 by means of a pin, or rivet 23 which passes through the inwardly extending upper and lower portions 8a and 8b, respectively, of the handle 8. Similarly, the other end of arm 21 is pivotally connected to the member 7 by means of a pin, or rivet 24 which passes through the inwardly extending upper and lower portions 10a and 10b, respectively, of the handle 10. The location of the pins 23 and 24 is determined by the fact that when the plate 18 is in its forward position, limited by the abutments 19 as shown in Fig. 1, the distance between the bolt 14 and the pins 23 and 24 should be slightly less than the distance from the bolt 14 to the rivet 22. Thus, when the members 6 and 7 are moved toward one another, the plate 18 will be moved backward until it reaches the position shown in Fig. 2.

Extending upwardly from the top of the channels 16 and 17 are stiffening ribs 25 and 26 respectively. These ribs support the guides 27 and 28 which are disposed at right angles to the stiffening ribs and perpendicularly with respect to the base 13, and are spaced from the base at their lower ends a distance sufficient to allow the plate 18 to pass freely under them. The web 29, joined to ribs 25 and 26 and the guides 27 and 28, is placed a short distance above the plate 18. A resilient means, such as the coil spring 30 is attached at one end, as at 31, to the web 29, and at the other end, as at 32, to the plate 18. Additional holes, such as 32a and 32b, may also be provided in the plate 18 so as to adjust the tension of the resilient means 30, which normally urges plate 18 forward to the position shown in Fig. 1.

The follower 33 is provided with a narrow central portion 34, and an extending rear portion 35. The central portion 34 is disposed between the guides 27 and 28 which permit vertical sliding movement of the follower 33. The rear portion 35 of the follower 33 is provided with a vertically extending hole 36, through which passes the rod 37. The lower end 38 of the rod extends through, and is positioned by, a hole 39 provided in the web 29. The upper end of the rod is provided with a cap 40, against which the upper end of a resilient means, such as the coil spring 41, is compressed. The lower end of the spring 41 presses against the rear portion 35 of follower 33. A hook 42, attached to one of the guides as at 43, engages an indented portion 44 of the cap 40 to assist in the positioning of the rod 37. When the machine is in use a plurality of partially formed staples S are stacked on the base 13 below the follower 33. The channels 16 and 17 at their forward ends are provided with inwardly extending projections 16a and 17a which, in effect, define a socket within which the lowermost of the staples S rests when the stapling machine is in the position shown in Fig. 1.

A magazine for the staples, having the outer wall 60, is fitted over the guides 27 and 28 and houses the supply of staples and helps keep them in alignment with the follower member, as will be described. The magazine is shown in Fig. 3 in longitudinal section. In Fig. 1, the magazine is shown in cross section, and in Fig. 7, the magazine is shown in cross section as taken on the line 7-7 of Fig. 3 and disassociated from other details so as to illustrate the relation between the magazine and the follower member clearly. The magazine includes side walls 60, which extend diagonally outwardly at an angle of about 45° from a connecting web 60a. Within the structure formed by the two walls 60 and the web 60a is another member substantially similar in shape but smaller, which is nested within the larger member. The smaller member has side walls 61 corresponding to the side walls 60 and the walls 61 are connected by a web 61a, which is substantially parallel to the web 60a. The inner member with walls 61 and 61a is rigidly secured to and held rigidly spaced from the walls 60 and 60a by two web members 62 which are located at the ends of the magazine. This structure provides an open channel between the opposite pairs of walls 60 and 61. Within that open channel, the arms of the follower member 33 project and are guided. Similarly, also, the stack of staple members S are positioned and held in alignment in advance of the follower member. It will be observed that the magazine is open between the walls 60 and 61 at both ends. The magazine may be secured to the device as, for example, to the guides 27 and 28, by any suitable means, either permanently or quick detachably.

The jaws 9 and 11 are offset with respect to their respective members 6 and 7 so as to place them in the same horizontal plane as the base 13. The jaws 9 and 11 are also provided with a horizontally extending recess defined by front walls 45 and 46, and side walls 47 and 48, respectively, as shown in Figs. 5 and 6. Within the recesses are catches 49 and 50, pivotally mounted on pins 51 and 52 which extend through the recesses vertically. Resilient means, such as the small coil springs 53 and 54, normally urge the catches inwardly or convergently, this movement being limited by the ears 55 and 56, which abut against the side walls 47 and 48 respectively.

To operate the device the cap 40 is slipped out from under the hook 42, and the rod, with its associated follower 33 is lifted out. A set of partially formed staples S is then inserted in the magazine with the open ends of the staples between the walls 60 and 61 and facing toward the jaws 9 and 11. The lowermost staple will then be resting on top of the plate 18 just to the rear of the extensions 16a and 17a. The follower 33 is then replaced on top of the uppermost staple and the rod 37 is pushed down until the lower end engages the hole 39, and the cap 40 engages the hook 42. The staples will then be in position as shown in Fig. 3. When the handles 8 and 10 are moved toward each other manually, the plate 18 will at the same time be moved rearwardly to a point just back of the staples, as shown in Fig. 2. When the plate has passed from under the lowermost staple it will drop down into the socket defined by the base 13 and the extensions 16a and 17a. As the pressure is removed from the handles 8 and 10, the tension of spring 30 will pull the plate 18 forward and at the same time cause the members 6 and 7 to move away from each other, resulting in the opening of the jaws

9 and 11. As the plate 18 moves forward it will push in front of it the staple which was just previously positioned in the socket. As the staple moves forward it will push the catches 49 and 50 outwardly against the pressure of the springs 53 and 54. When the staple reaches the end of its travel abutting against the front walls 45 and 46 of the recesses the catches 49 and 50 will snap back into the position shown in Fig. 5, and thus prevent any backward movement of the staple when the clinching operation begins.

With the staple in position in the jaws 9 and 11, when the handles 8 and 10 are next moved toward one another the jaws 9 and 11 will also be moved toward one another, causing the staple to be clinched, as shown by Figs. 2 and 6. At the same time the plate 18 is moved rearwardly as previously described, and another staple will drop down into the socket, so that when the plate again moves forward on release of pressure from the handles, this staple will replace in the jaws 9 and 11 the one previously clinched.

I claim:

1. In a stapling machine, a pair of staple-clinching jaws of generally channel shape in cross section, handles for moving said jaws toward one another for staple-clinching purposes, means for moving staples, one at a time, to said jaws, and rigid means carried by and pivotally mounted within the channels of said jaws for holding a staple during clinching thereof by the jaws.

2. In a stapling machine, a pair of staple-clinching jaws of generally channel shape in cross section, handles for moving said jaws toward one another for staple-clinching purposes, means for moving staples, one at a time, to said jaws, and spring pressed rigid catches carried by and pivotally mounted within the channels of said jaws for holding a staple during clinching thereof by the jaws.

3. In a stapling machine, a pair of staple-clinching jaws, handles for moving said jaws toward one another for staple clinching purposes, means for moving staples, one at a time, to said jaws, and means carried by said jaws for holding a staple during clinching thereof by the jaws, said holding means comprising a pair of rigid catch members, one pivotally mounted adjacent an end thereof on each jaw, and the free ends of the two catch members being spring urged to positions back of a staple in staple-clinching position in said jaws, with the consequent holding of the staple in position for jaw-clinching purposes.
